Primary Examiner — Thomas Johannes*Assistant Examiner* — Catherine Posthauer(74) *Attorney, Agent, or Firm* — Leanne Taveggia Farrell; Westman, Champlin & Koehler, P.A.(57) **CLAIM**

The ornamental design for a display fixture, as shown and described.

DESCRIPTION

FIG. 1 is a perspective view of a display fixture;
 FIG. 2 is a front view thereof, the back being identical;
 FIG. 3 is a left side view thereof, the right side being a mirror image; and,

FIG. 4 is a top view thereof.

The broken lines shown in the drawings are included for purposes of illustrating portions of the display fixture and form no part of the claimed design.
